US00D817951S

(12) **United States Design Patent** (10) **Patent No.:** **US D817,951 S**
(45) **Date of Patent:** **** May 15, 2018**

(54) **MOBILE COMPUTER**

(71) Applicant: **Getac Technology Corporation**,
Hsinchu County (TW)

(72) Inventor: **Chia-Wei Chang**, Taipei (TW)

(73) Assignee: **GETAC TECHNOLOGY
CORPORATION**, Hsinchu County
(TW)

(**) Term: **15 Years**

(21) Appl. No.: **29/572,883**

(22) Filed: **Aug. 1, 2016**

(51) LOC (11) Cl. **14-02**

(52) U.S. Cl.

USPC **D14/341**

Tingkang Xia, Esq.

(57) **CLAIM**

The ornamental design for a mobile computer, as shown and described.

DESCRIPTION

FIG. 1 is a top front right perspective view showing a first embodiment of my new design;

FIG. 2 is a bottom rear left perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a top front right perspective view showing a second embodiment of my new design;

FIG. 10 is a bottom rear left perspective view thereof;

FIG. 11 is a front view thereof;

FIG. 12 is a rear view thereof;

FIG. 13 is a left side view thereof;

FIG. 14 is a right side view thereof;

FIG. 15 is a top view thereof;

FIG. 16 is a bottom view thereof;

FIG. 17 is a top front right perspective view showing a third embodiment of my new design;

FIG. 18 is a bottom rear left perspective view thereof;

FIG. 19 is a front view thereof;

FIG. 20 is a rear view thereof;

FIG. 21 is a left side view thereof;

FIG. 22 is a right side view thereof;

FIG. 23 is a top view thereof; and,

FIG. 24 is a bottom view thereof.
